UNITED STATES PATENT OFFICE

2,035,852

DRILLING APPARATUS

Clinton L. Walker, Piedmont, Calif.

Original application May 11, 1932, Serial No. 610,633. Divided and this application November 7, 1933, Serial No. 696,967

4 Claims. (Cl. 255—74)

This application is a division of my co-pending application entitled "Deep well drilling and coring system," filed May 11, 1932, and bearing Serial No. 610,633, Patent No. 1,996,132, issued April 2, 5 1935.

The invention relates to deep well drilling equipment and particularly pertains to an apparatus for positioning and removing collapsible drilling bits at the lower end of the drill stem 10 while the latter remains in the well bore.

In my Patent No. 1,978,119, issued October 23, 1934, I have described and claimed an improved drilling bit which may be run in through the drilling stem and readily assembled on the lower 15 end thereof so that the proper weight may be imposed on, and proper torque applied to, the bit to effect the drilling operation. The bit is also capable of being disconnected from the drill stem while the same remains in the bore and removed 20 upwardly through the drilling stem.

It is the principal object of my present invention to provide an improved apparatus for use in expeditiously running in a bit of the character referred to downwardly through a drill stem and 25 positioning it for operation at the lower end thereof, said apparatus being also capable of use in operatively engaging the bit when the latter is connected to the drill stem to disconnect the bit from the drill stem and withdraw it upwardly through the stem.

In carrying the invention into practice, I provide a piston-like member which reciprocally fits the interior of the drill stem so that it may be readily passed downwardly through the drill stem 35 by fluid pressure exerted against its upper end and thereby position a bit at the lower end of the stem. The piston-like member referred to is equipped with a mechanism for operatively engaging a collapsible bit while the latter is assembled at the lower end of the drilling stem to disengage the same from the drill stem and withdraw it upwardly through the drill stem.

One form which the invention may assume is exemplified in the following description and illustrated by way of example in the accompanying drawing in which the figure is a fragmentary view, in central vertical section, through a drill stem showing a collapsible bit mounted therein with my improved apparatus also mounted in the 45 stem for operation.

Referring more particularly to the accompanying drawing, 10 indicates a well bore within which a drill stem 11 is positioned. My present invention is particularly concerned with positioning a collapsible drilling bit 12 at the lower end of the

drilling stem 11 and in removing the same from the drilling stem.

The collapsible drilling bit 12 may be constructed in the manner illustrated and described in my Patent No. 1,978,119, issued October 23, 5 1934. In general, this bit includes a bit body 14, which is of a diameter enabling it to be passed downwardly through the drill stem. This bit body carries two pivotal blades 15 which may be relatively positioned so that they will pass downwardly through the drill stem but which are capable of extending outwardly at the lower end of the drilling stem when in drilling position. These two blades 15 are connected to a toggle mechanism and to a trip member 17 which is 10 reciprocally mounted in the upper end of the bit body 12. Upward movement of this trip member 17 relative to the bit body 12 causes the blades 15 to be moved about their pivotal point and withdrawn to a position enabling them to pass 15 upwardly through the drill stem. When this member 17 is released, springs 18 tend constantly to expand the blades to a drilling position.

Some difficulty has been experienced in lowering a collapsible bit such as here illustrated 25 downwardly through the drill stem, due to the fact that the latter is usually filled when in the bore with a heavy mud fluid which must be displaced by the bit as it passes downwardly through the stem. For this reason I have provided the apparatus described in the present application 30 which includes a piston-like member 19, having a cup leather 20 at its upper end. I contemplate inserting this piston-like member 19 into the drill stem immediately following the insertion of 35 the collapsible bit 12 and then, by means of fluid pressure created by pumps on the surface, force the piston-like member 19 downwardly through the drill stem and consequently force the collapsible bit 12 downwardly through the drill stem. 40

It will be noticed that the piston-like member 19 is provided with a transverse slot in its lower end, and mounted within this slot is a pair of tongs 21. The tongs 21 consist of a pair of pivotal jaws 22 pivoted about a transverse pintle 23. The 45 ends of this pintle 23 are secured in the piston-like member 19, as illustrated. The upwardly extending arms 24 of the jaws 22 extend upwardly within the piston-like member 19 and are connected at their upper ends to a pull rod 25 through 50 the medium of toggle links 26. A pair of springs 27 are also arranged within the piston-like member 19 and are connected at their upper ends to the lower end of the trip rod 25 and at their lower ends to the pintle 23. These springs constantly 55

urge the jaws 22 apart. But, however, when the tension of these springs 27 is overcome by an upward pull on the trip rod 25, the jaws 22 are moved toward each other to an engaging position. The jaws 22 are so formed that when they are moved into engaging position they will engage a knob 28 formed at the upper end of the trip member 17 and thereby form an operative connection between the piston-like member 19 and the collapsible drilling bit 12.

It will be noticed that the lower extremity of the piston-like member 19 is slightly in advance of the lower extremity of the jaws 22 so that the lower end of the piston-like member will abut the upper end of the bit body 14 of the collapsible bit 12. Therefore, when fluid pressure is exerted at the upper end of the piston-like member 19, the pressure will be transmitted to the collapsible drilling bit 12 by reason of the engagement of 20 the piston with the upper end of the bit body.

The upper end of the piston-like member 19 is provided with circulating ports 29 which are controlled by a valve 30 formed as a part of the trip rod 25. When the tongs 22 are disengaged from 25 the trip member 17, the valve 30 is seated preventing fluid from passing downwardly from the piston-like member 19. However, when the trip member 25 is moved upwardly to form an operative connection between the piston-like member 30 19 and the collapsible drilling bit 12 through the medium of the tongs 21 and the trip member 17, the valve member 30 is unseated, enabling fluid to pass freely downwardly through the piston-like member 19. This reduces the resistance of 35 the fluid in the drill stem above the piston-like member 19 to the upward movement of the piston when withdrawing the piston through the drill stem; that is to say, in withdrawing the piston from the drill stem, it is unnecessary to lift 40 the entire fluid column in advance of it.

For operating the trip rod 25, it may be connected at its upper end to a cable or other line 31. To enable the piston 19 to be withdrawn upwardly through the drill stem without operating the 45 tongs 21, the piston is connected to a second cable or line 32 by the medium of an eye-bolt 33, which is connected to the upper end of the piston at an eccentric point.

In operation of the device, assuming that the 50 drill stem is positioned in the well bore with a collapsible drilling bit at the lower end thereof and it is desired to replace the bit, the piston-like member is connected to the cables 21 and 32 and inserted into the drilling stem. Pump pressure 55 is then built up in the drilling stem above the piston-like member 19, and by means of this pressure, the piston-like member 19 is forced downwardly until it engages the upper end of the body of the collapsible drilling bit 12. At this point 60 an upward pull is exerted on the cable 31 which moves the trip rod 25 upwardly relative to the piston-like member 19. This movement moves the jaws 22 to engaging position, engaging the under side of the knob 28 of the trip member 17 of 65 the drilling bit 12. A continued upward pull on the cables 31 and 32 then moves the trip member 17 of the bit upwardly relative to the bit body 14. This is accompanied by collapsing of the bit, and as the bit collapses, the entire bit will move 70 upwardly in the drill stem, together with the piston-like member 19. The bit may then be en-

tirely withdrawn from the drill stem and a new bit inserted into the drill stem.

After the new bit has been inserted, the piston-like member 19 is again inserted into the upper end of the drill stem and pump pressure created 5 to force the same, together with the bit 12, downwardly through the stem. When the bit reaches the proper point, it will expand as described in my patent above referred to, and form a weight-sustaining and torque-transmitting connection 10 between the bit and the drill stem. An upward pull is then exerted on the cable 32 to elevate the piston 19 in the drill stem an amount sufficient to prevent engagement of the tongs 21 with the trip member 17. A pull may then be 15 exerted on the cable 31 to move the valve 30 to open position so as to minimize the resistance of the fluid in the drill stem to the upward movement of the piston.

From the foregoing it is obvious that I have 20 provided an improved apparatus for positioning a collapsible drilling bit in the lower end of the drill stem while the same remains in the well bore, and disconnecting such a bit from the drill stem and removing it upwardly through the drill 25 stem.

While I have shown the preferred form of my invention, it is to be understood that various changes may be made in its construction without departing from the invention as defined in the 30 appended claims.

Having described my invention, what I claim and desire to secure by Letters Patent is—

1. In a well drilling organization including collapsible rotary tools capable of passing through 35 a drill stem, a hydraulic piston fitting the interior of the drill stem and movable co-axially therein, and means carried by said piston and operable from the upper end of the drill stem while the piston is at the lower end thereof to 40 form a detachable connection between the same and the rotary tools.

2. In a well drilling organization including collapsible rotary tools capable of passing through a drill stem, a hydraulic piston fitting the interior 45 of the drill stem and movable therein, and means carried by said piston to detachably connect the same with rotary tools, said means being operative from the mouth of the bore when the piston is adjacent the lower end of the drill stem. 50

3. In a well drilling organization including collapsible rotary tools capable of passing through a drill stem, a piston fitting the interior of the drill stem and movable co-axially therein, tong means carried by the piston and operative from 55 the mouth of the well to connect the piston to or disconnect the piston from a rotary tool in the lower end of the drill stem.

4. In combination with a hollow drill stem, a collapsible bit capable of being passed through 60 the drill stem and operatively assembled on the drill stem at the lower end thereof, a hydraulic piston fitting the interior of the drill stem, and means carried by said piston for connecting it with and disconnecting it from said bit while the latter is at the lower end of the drill stem for collapsing said bit and withdrawing the same 65 upwardly through the drill stem together with the piston.
